UNITED STATES PATENT OFFICE

JOHN M. FEEDERS, OF BUFFALO, NEW YORK, ASSIGNOR TO FEEDERS MANUFACTURING COMPANY, INC., OF BUFFALO, NEW YORK, A CORPORATION OF NEW YORK.

METHOD OF MAKING UNITS FOR RADIATOR-CORES.

1,322,553.

Specification of Letters Patent. Patented Nov. 25, 1919.

Original application filed April 24, 1916, Serial No. 93,118. Divided and this application filed August 4, 1917. Serial No. 184,445.

To all whom it may concern:

Be it known that I, JOHN M. FEEDERS, a citizen of the United States, residing at Buffalo, in the county of Erie and State of New York, have invented new and useful Improvements in Methods of Making Units for Radiator-Cores, of which the following is a specification.

This invention relates to a method of 10 making units for the cores of radiators which are more particularly employed for cooling the water of explosion motors in motor vehicles.

It is the purpose of this invention to improve the construction of the individual 15 units of the core so as to hold the several members thereof more securely in position relatively to each other while assembling the core and also while the same is completed and to accomplish this in a manner 20 which will expedite the manufacture of the radiator and reduce the cost of production and without sacrificing the efficiency of the radiator.

25 This application is a division of an application filed by myself April 24, 1916, Serial #93,118.

In the accompanying drawings:

Figure 1 is a fragmentary front elevation, 30 partly in section, of a radiator core having its units constructed in accordance with my invention, the section being taken on line 1—1, Fig. 2. Fig. 2 is a horizontal section taken on line 2—2, Fig. 1. Fig. 3—8 are fragmentary longitudinal sections showing different steps or stages in the method 35 of making up a radiator unit embodying my improvements. Fig. 9 is a fragmentary vertical section similar to Fig. 1 but showing a slightly modified form of my improvements. Fig. 10 is a horizontal section taken on line 10—10, Fig. 9.

Similar characters of reference indicate 40 corresponding parts throughout the several views.

A radiator constructed in accordance with my invention comprises a plurality of water tubes 1 which are preferably of zig-zag or serpentine form and a plurality of air tubes 50 2 which are arranged at right angles to the water tubes. The water tubes in the par-

ticular example shown in the drawings are arranged in a vertical position and the air tubes are arranged horizontally but any other disposition of these conduits may be 55 made, if desired. In the completed radiator the upper and lower ends of the water tubes are connected with the upper and lower water headers or boxes of a radiator in any suitable and well known manner so that the 60 water from the explosion engine which is to be cooled traverses the water tubes and is cooled by the passage of air through the air tubes between the several water tubes.

The several water tubes and air tubes are 65 preferably constructed of a plurality of transversely corrugated or crimped strips of metal which are so assembled that one or more vertical rows or tiers of air tubes are formed between each pair of adjacent water 70 tubes. In the example shown in the drawings two of such corrugated strips 3, 3 are employed to form the walls of each water tube, and one or more additional corrugated strips 4 are used to form one or more radiat- 75 ing webs, fins or disks between the opposing walls of two water tubes to produce there- with one or more tiers of air tubes between adjacent water tubes.

The summits 5 of the corrugations on one 80 side of each water tube wall extend uniformly or continuously from one longitudinal edge thereof to its opposite longitudinal edge while the summits of the corrugations on the opposite side of each of these 85 walls have a receding central part 6 and laterally off-set end portions 8, 8 at the opposite longitudinal edges of this wall. The strips constituting the walls of each water tube are assembled so that the convex sides 90 of the end portions of the continuous summits of one of these walls engage with the concave sides of the off-set portions of the summits of the other companion wall of a water tube, thereby causing the longitudinal 95 edges of these two walls to engage with each other throughout their length while the intermediate parts of these walls are separated and form a conduit for the passage of the water through the same, as shown in Figs. 100 1 and 2.

Each radiating web is preferably so

formed that the convex sides of the summits 9 of its corrugations are continuous between its longitudinal edges. When only one radiating web is arranged between the opposing walls of two water tubes, as shown in Figs. 1-8, the convex sides of the summits of this radiating web engage alternately with the convex sides of the summits of the adjacent walls of two water tubes and form with the latter two vertical rows or tiers of air tubes in connection with these walls, as shown in Figs. 1, 3-8.

In order to facilitate the manufacture of this core and hold the parts reliably in place relatively to each other the two walls of adjacent water tubes are constructed from a continuous strip of metal which is so formed that a wholly integral head 10 is formed between two of the corresponding ends of these walls which is integral with both of these walls, and a partly integral or sectional head is formed between the composite ends of these walls. This last mentioned head is composed of two sections 11, 13 which are interlocked with each other and one of which is formed integrally with one end of one of these walls while the other section is formed integrally with the corresponding end of the other wall. The radiating web or webs which are arranged between the two walls of adjacent water tubes are also preferably interlocked at their opposite ends with the two heads connecting the corresponding ends of these walls so as to form a complete and substantial unit the members of which are reliably connected and not liable to become displaced during the manufacture of the radiator or while the same is in use and which can be readily and quickly assembled with similar units for producing the radiator core preparatory to assembling the latter with the headers previously referred to.

When a radiator unit of this character is constructed having but a single radiating web or fin between two water tube walls, as shown in Figs. 1-8, the method of assembling the same and the structure resulting from this method is as follows:

A previously formed or corrugated strip of metal having a total length greater than the combined length of the water tube walls and the connecting heads is first laid out and a previously formed or corrugated radiating web is deposited upon one-half of the continuous wall and head strip at one end thereof, this web having a length somewhat greater than the total length of the completed unit. That portion or half of the wall strip which is not covered by the radiating web just referred to is now doubled with reference to the covered part of this strip so as to form the two walls of the unit and arranged parallel or side by side and inclose the radiating strip or web

between the same, as shown in Fig. 3. The continuous turn or bight between the two walls of this unit is now bent or folded reversely into approximately the shape of the letter S so as to form a head 10 of this shape which is integrally connected at its opposite ends with the adjacent ends of both of the walls of the unit and has a transverse channel 15 which opens outwardly toward the exterior of the unit and another transverse channel 16 which opens inwardly to the internal space between the two walls of this unit, this being due to the connection of one extremity of the S-shaped head with one of these walls while the other extremity thereof is connected with the other wall, as shown in Fig. 4. At the same time that the doubled or reversely folded head 10 is formed which is integral with both walls of the unit the corresponding end 17 of the radiating web between the same is also preferably folded or doubled upon itself into substantially U-shaped form so that the outer leg or part of this U-shaped end of the web is arranged in the inwardly opening channel 16 of the integral head, as shown in Fig. 4, thereby securely interlocking this end of the radiating web with the respective head of the unit.

The opposite end portion of the upper wall and the corresponding end portion of the radiating strip are now lifted and the corresponding end of the lower wall is bent inwardly and over the companion wall for a short part of its length, as shown in Fig. 5, and then this end part is bent, doubled, or folded reversely upon itself so as to form the section 11 of the head for this end of the unit which section has substantially the shape of the letter S, as shown in Fig. 6, and forms an outwardly opening channel 19 and an inwardly opening channel 20. The other end portion 21 of the web and the other end portion 13 of the other wall of the unit are now lowered upon the head section 11 which has just been formed, as shown in Fig. 6, and then the respective ends 13, 21 of the upper wall and the radiating web are folded or bent so that the free end 13 of the upper wall assumes the shape of the letter U and the adjacent end 21 of the radiating web assumes the form of a flange. The U-shaped end 13 of the upper unit wall forms the other section of the sectional head and is inserted in the outwardly opening channel 19 of the companion head section 11, and the flange 21 on the corresponding end of the web is arranged between the U-shaped head section 13 and the inner member of the companion S-shaped section 11, as shown in Fig. 7. These two head sections and the interposed flange 21 on the corresponding end of the web are now pressed tightly against each other so that the same become firmly interlocked, as shown in Fig. 8.

Fig. 8, thereby completing the radiating unit. After a plurality of such units have been assembled in the manner shown in Fig. 1 the opposite edges of the same are dipped 5 in solder for the purpose of sealing the joints between the walls of adjacent units so that they will not leak and also securing the webs to these walls and sealing the heads at opposite ends of the units so that water 10 can leak from the headers into the endmost air tubes in a manner which is customary in the manufacture of this class of goods.

When two transversely corrugated radiating strips 22, 22 are arranged between the 15 two transversely corrugated walls 23, 23 of a unit, as shown in Figs. 9 and 10, the convex sides 24 of the summits of the corrugations of each radiating web engage on one side of this web with the summits on one of these 20 walls and on the opposite side thereof with the summits of the corrugations of the other or companion radiating web. In this construction the two walls of a unit and the heads at opposite ends thereof are also constructed 25 from a continuous strip of metal which is folded upon itself so as to form the two parallel walls of the unit, a wholly integral head 25 at one end thereof which is integral with both walls, and a partly integral or sectional head at the opposite ends thereof which is composed of two sections 30 26, 27 one of which is integral with one of the walls and the other section being integral with the other wall of the unit. The wholly 35 integral head in this case is also bent into substantially S-shaped form so as to produce an inwardly opening transverse channel 28 and an outwardly opening transverse channel 29, said inwardly opening channel receiving flanges 30, 31 which are formed on the corresponding ends of the two radiating webs between the respective walls of the unit.

The sectional head at the opposite ends of the walls of the units shown in Figs. 9 and 45 10 are so constructed that the section 26 is of S-shaped form and provided with an outwardly opening channel 32 and the other 27 is made of a U-shaped form and arranged in the channel 32, and the adjacent ends of the 50 two radiating webs are provided with flanges 33, 34 which are arranged between the inner part of the S-shaped head section 26 and the U-shaped head section 27 at the respective ends of the walls. When a plurality of units 55 having two radiating strips are arranged in a core, the integral head of one unit is comparatively narrow and arranged at the top of the core and its sectional head comparatively wide and arranged at the bottom of the 60 core and the adjacent unit has its upper integral head made comparatively wide and its lower sectional head made comparatively narrow, as shown in Fig. 9.

By thus interlocking the radiating webs 65 with the opposite ends of the walls of the

unit between which the same are disposed displacement of these parts during the operation of manufacturing the radiator is avoided, thereby facilitating its manufacture and reducing the cost accordingly, and 70 in the completed condition of the radiator the same is also materially strengthened so that it is able to withstand the shocks and strains to which the same is subjected while 75 in use.

I claim as my invention:

1. The herein-described method of making a radiator unit having two outer walls and an intermediate web arranged between said walls which comprises taking a wall strip 80 for forming said walls which is of a length greater than twice the length of the completed unit and placing upon one half of said strip, while the latter is still straight, a web strip designed to form a web, then 85 folding the other half of said wall strip, not previously engaged with said web strip, over the top of the latter so as to form two outer walls of the unit, then interlocking said strips at the integrally connected ends 90 of said walls, and then interlocking said strip at the free ends of said walls.

2. The herein-described method of making radiator units which comprises taking a wall strip which is intended to form the outer 95 walls of the unit and laying the same out straight, said strip having a length greater than twice that of the completed radiator unit, placing a web strip of greater length than the length of the completed unit on 100 said wall strip so that this web strip covers approximately one-half of said wall strip adjacent to one end of the latter, folding the previously uncovered half of said wall strip over the top of said web strip so that the 105 latter forms a web between two walls formed by the doubled wall strip and two ends of said wall are integrally connected while the opposite ends thereof are disconnected, then interlocking the integrally connected ends 110 of the outer walls with the adjacent end of the web by crimping the same together, and then interlocking the opposite disconnected ends of said walls with the corresponding end of the web by crimping the respective 115 ends together.

3. The herein-described method of making a radiator unit which comprises taking a previously corrugated wall strip having a length equal to more than twice that of the completed unit and laying the same out flat, placing a previously corrugated web strip of a length greater than the completed unit on one-half of said wall strip adjacent to one end of the latter, doubling that part of the wall strip which is uncovered by the web strip over the latter so that the wall strip forms two outer walls which are integrally connected at one of their ends by a head and the opposite ends of the same are free 120

and the web strip between the same forms a web, then crimping the integral head and the adjacent end of the web so as to convert said head into S-shaped form and said web end into the form of a tongue which interlocks with a channel of said S-shaped head, then bending the opposite free end of one

of said walls to form a channel thereon, and then bending the corresponding ends of the other wall and the web opposite to the integral head into the form of a tongue and interlocking the same with the adjacent channel on the free end of the other wall. 10

JOHN M. FEDDERS.
